UNITED STATES PATENT OFFICE.

HARRY BITNER, OF FREEPORT, ILLINOIS.

LATCH.

1,124,278.

Specification of Letters Patent.

Patented Jan. 12, 1915.

Application filed February 11, 1914. Serial No. 817,970.

To all whom it may concern:

Be it known that I, HARRY BITNER, residing at Freeport, in the county of Stephenson and State of Illinois, have invented certain new and useful Improvements in Latches, of which the following is a specification.

My invention relates to certain improvements in latches of the class designed to exert a strong pull upon a door to draw it tightly and securely into a closed position. In latches of this sort it is desirable first that there shall be no projecting portions to catch upon the clothing; second that the operation of the latch in the opening of the door shall require only a single movement of one hand which should release the latch and open the door.

It is the purpose of my invention to provide a latch having a bolt which is provided with suitable means for giving it a constant tendency to move into a locked position with means for holding said bolt in the unlocked position when the door is open, also to provide a latch having a swinging bolt constantly urged by a spring toward the locked position with a dog arranged to move automatically into a position which holds the bolt in the unlocked position when the door is open.

To such end and others incidental thereto my invention consists in certain novel features embodied in the preferred construction which is shown in the drawing and the essential characteristics of which are pointed out in the claims at the end of this specification.

In the drawings Figure 1 is a front elevation of a complete latch in its locked position; Fig. 2 is an end elevation of the same with the parts in the same position; Fig. 3 is an end elevation of the parts in an unlocked position and Fig. 4 is a horizontal cross section in plane 4—4 of Fig. 1, through the pivot pin of the swinging bolt with a portion of the latter and the spring which operates it broken away to show the spring upon the pivot pin of the dog in the horizontal plane 4^a, 4^a, Fig. 1.

In these drawings A represents the opening edge of a door and B the frame or other part against which it closes. Upon the door is secured a lock casing or cover, C, in the end portions of which are mounted pivot pins of a swinging bolt, D, and an oscillating dog, E. These pivot pins are best seen

in Fig. 4 and are surrounded by coiled springs, d, e, each wound to give clock-wise rotation to its respective pivot pin. The swinging bolt D on the projecting end of the pivot pin d is provided with a depending handle, d¹, and a laterally projecting flange, d². A keeper, F, is secured to the frame adjacent to the edge of the door and has a laterally projecting lug, f, beneath which the flange d² may slide as the door is closing. Said lug f is suitably rounded and located with reference to the axis of the swinging bolt as to tighten the door against the frame when the flange is forced under the lug. The dog E on the end of the pivot pin e has a portion e¹, in line with the swinging bolt and arranged to swing downward and engage and hold the flange d² against a return movement when the bolt is swung into the unlocked position. When the dog and the bolt swing into the position seen in Fig. 3 they engage at e² to check the further movement of the dog and when they swing into the position seen in Fig. 2 they engage at e³ to check the further movement of the swinging bolt.

The operation of the latch is as follows: The handle d¹ is grasped and pulled away from the door, rotating the bolt to free the flange d² from the lug f after which the further pull upon the handle throws the door wide open. Meanwhile the dog E has slipped down the flange d² into the position seen in Fig. 3 where it blocks the return movement of the bolt while the door is open.

In closing the door it may be either slammed in the ordinary manner or may be closed by grasping the handle d¹. In either case when it reaches the position seen in Fig. 3 the top of the keeper F strikes the dog moving it up the flange d² and permitting said flange to wedge itself beneath the lug f. This it is caused to do by the spring wound upon its pivot pin.

It should be noticed that the flange d² is of considerable longitudinal extent so that it picks up the lug f before the door is sufficiently closed to bring the part of the flange which finally locks the door in contact with said lug.

The construction and arrangement of the various parts of the latch may be varied considerably without materially changing the advantages thereof and hence I do not desire to limit myself to the preferred forms here shown but will point out in the follow-

ing claims the various characteristics which I consider essential to my invention and it is my intention in said claims to cover all of the patentable novelty contained in my 5 invention over the prior art.

I claim as new and desire to secure by Letters Patent—

1. The combination with a door and the frame against which it swings of a latch 10 casing having suitable bearings, a bolt having a depending handle, a laterally extending pivot pin in one of said bearings and a laterally projecting flange between the same and the door frame, a dog having a laterally 15 projecting pivot pin in the other of said bearings and swinging into engagement with said flange to lock the bolt in the open position and a keeper having a laterally projecting lug arranged to engage said flange 20 to lock the door and to engage said dog as the door is closing to release said flange and permit it to move into the locked engagement.

2. The combination with a door and the 25 frame against which it swings of a latch casing having suitable bearings parallel with the door, a locking bolt pivoted in one of said bearings at the end of the casing, a locking dog pivoted in another of said 30 bearings adjacent to the bolt and adapted to lock the bolt in the open position, said dog and said bolt being arranged to mutually engage and limit their respective movements, and a keeper adapted for engagement 35 with the bolt to lock the door and with the dog to release the bolt from the open position.

3. The combination with a door and frame 40 against which it swings of a casing for the door having bearings parallel therewith, a swinging bolt having a laterally extending pivot pin in one of said bearings, a depending handle and a laterally projecting flange between its bearings and the frame, a dog 45 having a laterally projecting pin pivoted in another of said bearings and adapted to swing into engagement with the flange to

hold the bolt in the unlocked position, a spring upon the bolt pivot urging the bolt toward the locking position, a spring upon 50 the dog pivot urging the dog into engagement with the flange and a keeper for the frame having means of engagement with said flange to lock the door and with said dog to release the bolt therefrom.

4. The combination with a door and the frame against which it swings, of a latch casing, a bolt pivoted to said casing upon an axis substantially parallel with the door, a depending handle on said bolt substantially 55 at right angles to said axis, a laterally projecting flange on said bolt arranged between the axis thereof and the frame when the bolt is locked, a dog pivoted adjacent to said bolt upon an axis substantially parallel to the door, means of engagement between said dog and said bolt operating automatically to hold the bolt in the unlocked position when it is moved into that position, and a keeper arranged to engage with 60 said flange to lock the door and with said dog to release the bolt therefrom.

5. A combination with a door and its frame of a casing for attachment to the door, a swinging bolt pivoted thereto to 75 swing in a plane perpendicular to the door, a laterally extending locking flange on said bolt arranged between the bolt pivot and the frame when the bolt is locked and having an engaging surface of considerable longitudinal extent adapted to slide under the keeper, a dog adapted to automatically lock said bolt open and a keeper for the frame 80 adapted to engage with said dog to release the bolt and with said flange to lock the 85 door.

In witness whereof I have signed the above application for Letters Patent at Freeport, Illinois, this 4th day of February, A. D. 1914.

HARRY BITNER.
